COMBINED SINK AND UTILITY PEDESTAL OR SIMILAR ARTICLE

William F. Helwig, Jr., Downers Grove, Ill., assignor to
Avtec Industries, Incorporated

Filed Dec. 26, 1974, Ser. No. 536,418

Term of patent 14 years

Int. Cl. D23—02

U.S. Cl. D23—49

FIG. 1 is a perspective view of a combined sink and utility pedestal or similar article showing the front and one side.

FIG. 2 is an elevational view taken from the side opposite that shown in FIG. 1.

FIG. 3 is a rear elevational view thereof.

FIG. 4 is a bottom plan view thereof.

I claim:

The ornamental design for a combined sink and utility pedestal or similar article, substantially as shown and described.
